UNITED STATES PATENT OFFICE.

JAMES STANLEY, OF WASHINGTON, DISTRICT OF COLUMBIA.

MAIL-DELIVERER.

1,299,867.

Specification of Letters Patent.

Patented Apr. 8, 1919.

Application filed September 28, 1916. Serial No. 122,656.

To all whom it may concern:

Be it known that I, JAMES STANLEY, a citizen of the United States, residing at Washington, in the District of Columbia, have 5 invented certain new and useful Improvements in Mail-Deliverers; and I do declare the following to be a full, clear, and exact description of the invention, such as will enable others skilled in the art to which it applies to make and use the same, reference being had to the accompanying drawings, and to the letters and figures of reference marked thereon, which form a part of this specification.

15 My invention relates to mail-bag catchers and deliverers. It has for its object to provide a receptacle for the mail-matter, large or small, whether for receiving or delivering the mail from the car which will securely 20 hold the mail until it is to be discharged therefrom, and will readily respond to the operating opening member, and from which also the quick discharge of the mail will be accelerated by a gravitating weight within 25 the receptacle; also to provide for delivering mail from more than one receptacle, in succession, as the mail car passes a station, with a different character of mail matter placed in the different receptacles, or mail of a miscellaneous character placed in one or more of 30 the receptacles; also to provide a construction in which the impact or effects thereof will be reduced to the minimum or small degree by reason of the details of construction employed, thereby lessening the liability 35 of damage or impairment of efficiency in the operating parts.

To the accomplishment of the foregoing and such other objects as may hereinafter 40 appear the invention consists in the features hereinafter described and then sought to be clearly defined by the claims, reference being had to the accompanying drawings forming a part hereof, and in which

45 Figure 1 is a side elevation of a car, and crane, and receiving trough, embodying my invention;

50 Fig. 2 is a top plan view of the same parts, with portions of the car broken away to show the location of certain parts at the doors of the car;

55 Fig. 3 is a cross section on the line 3—3 of Fig. 1, looking in the direction of the arrows.

Fig. 4 is a detail view, with the receptacle

in vertical section, showing a mail-bag and accelerating weight therein;

Fig. 5 a vertical section through the receptacle on line 5—5 of Fig. 4, looking in the direction of the arrow;

Fig. 6 is a vertical section through the receptacle with the accelerating weight in its lowermost position;

Fig. 7 a bottom plan view of the receptacle with the swinging bottom closed;

Fig. 8 is a detail sectional view on the line 8—8 of Fig. 3;

Fig. 9 is a detail view showing manner of suspending the receptacle from the end of the crane;

Fig. 10 is a plan view of one of the sockets for receiving the ends of the post from which the receptacles are supported.

In the drawings the numeral 1 designates a mail car which in its general construction 75 may be of any well known approved type. For the purpose of receiving mail suspended by a crane along side the track it is formed with an opening 2 in its top which may be of suitable dimensions and best located for 80 the purpose, and this opening is provided at its sides with folding or hinged doors 3 which when the mail is to be received are raised and will bear against suitable stops 4, although if desired the door might be made 85 to slide which is not so shown because within the skill of the mechanic. Toward each end the car is provided at the top with arms 5 of suitable form and material suitably hinged or pivoted at one end by pintles 6 to 90 the top or roof of the car, and the two arms are connected together at their other ends preferably by a flexible cable or cross bar 7 which when the arms are raised will serve 95 to engage the latch of a mail containing receptacle hereinafter described so as to release the catch and open the receptacle for delivery of the mail. These arms are raised by means of a suitable rope or cable 9 extending into the car within reach of the 100 mail clerk, and provided with a suitable knob or enlargement 10 which when the rope or cable is slipped into a slot 11 formed in a cross piece 12 will bear against the under- 105 side of the cross-piece and hold the arms in their raised position, as shown at the left of Fig. 1 and which may be slackened to permit the arms to lie upon the top of the car as shown in full lines at the right of Fig. 1. The arms are also attached by cables 110

or chains 8 to the car so as to limit the arms to the proper elevation for their cross connecting cable or bar to engage the latch of the mail receptacle. When the car has 5 passed the station the doors are closed and the catch releasing device lowered. At the station, alongside the track, is erected one or more cranes 13 for supporting the mail containing receptacles which cranes may be 10 of any suitable construction but preferably of the construction illustrated. At its end the crane is provided with a bracket 14 within which is journaled a sheave or pulley 15 over which passes a rope or cable 16 for 15 raising and lowering the mail containing receptacle, said cable passing through guides 17 attached to the crane and one end is connected to a drum 18 journaled in a bracket 19 and adapted to be rotated by a 20 handle 20 and held by a ratchet and pawl device 20^a of any approved form so that the cable may be wound and unwound to and from the drum. To the other end of the cable is attached the mail containing receptacle 21. This receptacle is made of any suitable material and is provided with a bail 22 which at its upper end is attached to a block 23 to which the cable is attached and which when the receptacle is in delivering 25 position will fit between the face of the sheave or pulley 15 and the side of the bracket 14 so as to steady the receptacle in its suspension, and also enables the receptacle to be turned a half revolution and held 30 in that position so as to present the latch of the receptacle properly toward the traveling mail car if moving in the opposite direction to that indicated by the arrows in Fig. 1 of the drawing. The receptacle is provided 35 with a swinging bottom 24 which is held closed by a swinging latch 25 attached to the receptacle and which has side projections 26 adapted to fit beneath the bottom when the latch is in its locking position so 40 as to hold the bottom closed, the latch at such time fitting in a notch 27 formed in the edge of the bottom. The receptacle is also provided with a weight 28 designed to rest on top of the mail matter in the receptacle 45 so as to accelerate the discharge of the mail matter when the bottom is opened, said weight being provided with a hand-grip 30 for lifting it and with chains 31 for attaching the weight to the receptacle and 50 for limiting its downward movement. The swinging bottom is also preferably provided with a projecting lip 32 designed to strike against the side of the receptacle when the bottom is opened and thus restrict the backward swing of the bottom and at the same 55 time make the latter serve to direct the mail matter into the opening in the top of the car. Under the construction described the mail matter contained in a mail bag 33, or in 60 separate packages or parcels, is placed with-

in the receptacle with the bottom closed and held by the latch and with the accelerating weight resting on top thereof, and the receptacle raised to the overhanging arm of the crane by means of the drum or windlass 70 described. As the train approaches the station the doors to the sides of the opening in the top of the car are lifted and the arms with their connecting member raised so that as the car passes under the receptacle, the 75 cross member of the arms will strike the depending latch of the receptacle thereby releasing the bottom which will swing open and permit the mail matter to be discharged and which will drop through the opening 80 in the top of the car and be deposited on the floor of the car or on to a table provided to receive it, the weight within the receptacle accelerating and insuring the quick delivery of the mail matter from the receptacle. If 85 the train pass in the opposite direction to that indicated by arrows in Fig. 1, the receptacle will be turned to present the locking latch at the opposite point to that shown in Fig. 1 and the receptacle held in that 90 position by engagement of its bail block 23 between the sheave 15 and side of the bracket 14 as before mentioned, and the latch releasing arms at the opposite end of the car raised so that their cross member will engage the locking latch and release the bottom of the receptacle for discharge of the mail matter as described.

If the mail matter is to be delivered from the car instead of to the car, a receptacle, or receptacles 21^a similar to the receptacle 21 is provided for the mail matter, except that the suspending bail is omitted. The receptacle will fit within bands or rings 34 carried by arms 35 attached to a post 36 journaled in sockets 37 and 38, the latter preferably being formed in two parts as shown in Fig. 10 so that when the post is to be changed from one position to another it may readily be removed from its sockets by releasing one section from the stop pin 39 and swinging it on its pivot 40 so as to release the post. The rings or bands 34 are formed with notches or slots 41 and the receptacle 21^a with side projecting pins 42 115 to fit in the slots so as to secure the receptacle in proper position for the locking latch of its bottom to be engaged by the releasing device for opening the bottom for discharge of the mail matter. By turning the 120 receptacle one half a revolution the position of the locking latch will be changed so as to render the receptacles operative in whichever direction the train is running. In delivering from the car a trough 43 is placed 125 alongside the track and it is provided with upright arms or posts 44 connected one to the other by a member 45, preferably a flexible cable, drawn taut, so that as the train passes the locking latch of the receptacle will 130

engage the cross member and be released so that the bottom may swing open and the mail matter be discharged into the trough. This releasing member is shown as applied 5 at one end of the trough but it is obvious that the trough may be made longer and the releasing member placed midway or otherwise between the two ends of the trough so that if the mail be delivered from the 10 same side of the car in the travel of the train in one direction, or the other, for instance on a single track road, the mail will be delivered into the trough. As this is an obvious change it is not illustrated. There 15 may be several deliveries from the car at any station, for illustration I have illustrated four, two deliveries from each of two doors of the car; and if it be desired to change the delivery from one side to the 20 other, the supporting posts may be released from their sockets and transferred from one side to the other, or if it be desired to deliver from both sides at one station or another, the supporting posts and receptacle 25 carrier may be duplicated so as to be applied to each door at both sides of the car. For steadyng the arms carrying the receptacles when swung outward to deliver the mail, the side frames of the door may be 30 formed with recesses 46 to receive the arms as clearly shown in Figs. 3 and 4 of the drawing, and if desired screw bolts 47 with operating handles 48, or other suitable means, may be employed for temporarily locking 35 the arms in their outward extended positions. A few turns of these bolts will unlock the arms so that they may be swung to position within the car.

It will be observed that in delivering both 40 from the crane and from the car provision is made for shifting or changing the mail receptacle so that it will be operative to discharge the mail in whichever direction the train is running, and also for securely holding it in such position so as to insure prompt 45 action of the operating parts. It will further be observed that the mail may be delivered in sacks, or in separate packages or parcels, or both, from the same or different 50 receptacles, and that whether much or little mail matter be placed in the receptacle it will be promptly discharged therefrom at the proper time by reason of the accelerating weight resting on top of the mail matter. The parts of the deliverer are of such 55 simple construction that they can be made and installed at comparatively small cost, and are strong and durable and capable of 60 withstanding the shocks to which devices for the same purpose are subjected.

Having described my invention and set forth its merits, what I claim is:

1. A mail deliverer, comprising a mail-holding receptacle provided with a swinging bottom, a swinging latch attached to the 65

receptacle and having a portion depending below the bottom of the receptacle and provided with side projections above its lower portion for engaging the swinging bottom to hold the same closed, and a latch releasing device supported in relation to the receptacle to engage the swinging latch to release it from holding engagement with the swinging bottom. 70

2. A mail deliverer, comprising a mail-holding receptacle provided with a movable bottom, a latch attached to the receptacle and engaging the movable bottom to hold the same closed, a latch releasing device supported in relation to the receptacle to 75 engage the latch to release it from holding engagement with the movable bottom, a support for the receptacle, and means for holding the receptacle in either of two positions without removal of the support to 80 present the latch in operative relation to the releasing device.

3. A mail deliverer, comprising a mail-holding receptacle provided with a swinging bottom, a latch attached to the receptacle and engaging the swinging bottom to hold the same closed, a latch releasing device supported in relation to the receptacle to engage the latch to release it from holding engagement with the swinging bottom, 90 a crane provided with means for suspending the receptacle from the crane, a bail attached to the receptacle, and a member attached to the bail and disposed in relation to the overhanging arm of the crane to engage with portions of the crane to sustain the receptacle in either of two positions to 95 present the latch in operative relation to the releasing device.

4. A mail deliverer, comprising a mail-holding receptacle provided with a swinging bottom, a swinging latch attached to the receptacle and engaging the bottom to hold the same closed, a car formed with an opening in its roof to receive mail discharged from the receptacle, and a device for releasing the latch of the receptacle, said device comprising a swinging arm attached to the car roof at one end of the opening therein and normally resting in a 105 lowered position on the car top, and means connected with said arm and extending into the car for raising the arm into position to engage the receptacle latch, said arm being suspended in its raised position so as to 110 drop by gravity when released. 115

5. A mail deliverer comprising a mail-holding receptacle provided with a swinging bottom, a latch attached to the receptacle for holding the bottom closed, a releasing device positioned to engage the latch to release the same when the bottom of the receptacle is to be opened, means for supporting the receptacle and moving it into position for delivering mail therefrom, and 125 130

means for securing the receptacle in different adjusted positions to present its latch in operative relation to said releasing device.

6. A mail deliverer comprising a mail holding receptacle provided with a movable bottom, a latch attached to the receptacle for holding the bottom closed, means for releasing the latch when the bottom is to

be opened and mail is to be delivered from the receptacle, means within the receptacle 10 to rest upon mail matter for accelerating the delivery of mail matter from the receptacle and means for limiting the descent of said accelerating means.

In testimony whereof I affix my signature. 15
JAMES STANLEY.

Copies of this patent may be obtained for five cents each, by addressing the "Commissioner of Patents, Washington, D. C."
